HIGH-FREQUENCY HEATING APPARATUS

John A. Redmond, Baltimore, Md., assignor to Westinghouse Electric Corporation, East Pittsburgh, Pa., a corporation of Pennsylvania

Application August 12, 1950, Serial No. 179,078

4 Claims. (Cl. 219—10.79)

My invention relates broadly to high-frequency heating; but, more particularly, my invention is directed to improvements in apparatus for the high-frequency heating of a tubular object, by tubular object meaning an object having a central opening capable of receiving an electrical conductor.

A purpose of my invention is to provide a high-frequency heating apparatus capable of heating a tubular metallic object by heating currents magnetically induced therein in a manner that causes the currents to flow lengthwise, or axially, of the opening in the object, instead of in a path around the axis as taught by the prior art.

A further object of my invention is to provide an induction heating apparatus of a type described, capable of heating a tubular object, such as a small hollow shaft or bushing, the apparatus being such as to be capable of simultaneously heating the inner and outer surfaces of the object.

In accordance with the teachings of my invention, I provide a pair of nested inner and outer heating conductors which are connected electrically so that current flows lengthwise or axially along both of them. The conductors are spaced, and the inner conductor is placed inside of the opening of the tubular object to be heated, preferably out of contact with the conductors. When current flows through the conductors, the object is heated. In the case of a ferrous object, the apparatus can be arranged for hardening a surface of the ferrous object by perforating a wall of one or both of the conductors and passing a quenching-liquid through the perforations or openings at a suitable time.

Objects, features and innovations of my invention, in addition to the foregoing, will be discernible from the following description of illustrative apparatus embodying the invention. The description is to be taken in conjunction with the accompanying simplified drawings, in which details such as work-handling holders, and so forth, are omitted in the interest of clarity and brevity. In the drawings:

Figure 1 is a somewhat diagrammatic view of apparatus embodying my invention;

Fig. 2 is a sectional view substantially on the line II—II of Fig. 1;

Fig. 3 is a vertical sectional view of a preferred embodiment of my invention, the section-plane being indicated by the broken line III—III in Fig. 4;

Fig. 4 is a plan view of the apparatus of Fig. 3;

Fig. 5 is a sectional view substantially on the line V—V of Fig. 3; and

Fig. 6 is a sectional view substantially on the line VI—VI of Fig. 4.

Figs. 1 and 2 show a simplified induction heating apparatus, illustrative of the broad principle of my invention, that can be used for heating bushings. The apparatus comprises an induction heater which is indicated in its entirety by the reference numeral 2. The induction heater 2 comprises a straight inner heating conductor 4 and a straight outer heating conductor 6. The conductors are cir-

2

cular in cross section and are made of a highly conducting metal such as copper. The outer conductor 6 is hollow so that the inner conductor 4 can be nested therein, preferably parallel and concentric therewith. The bottom ends of the heating conductors 4 and 6 are intimately electrically connected together by a conductor-means comprising a direct electrical connection-conductor shown as an annular plate 8 which is also made from a highly conductive metal.

The heating conductors 4 and 6 are radially spaced, i. e., they are separated in a direction perpendicular to their common axis, so as to provide a work-receiving space 10 therebetween. This space 10 is generally annular in cross section and is bounded by the outer or facing surface of the inner heating conductor 4, the inner or facing surface of the outer heating conductor 6, and the inner or facing surface of the connection-plate 8.

A tubular object 12, in the form of a cylindrical tube, is supported in the work-receiving space 10 in any suitable manner for heat treatment. A work-supporting means is shown as comprising a plurality of spaced piers 14, carried by the connection-plate 8. Each pier has a seat or notch for receiving an end of the tubular object 12. The piers are made of a material that will stand a high temperature, and molybdenum has been found satisfactory for this purpose.

At the ends of the heating conductors 4 and 6 which are opposite to those associated with the connection-plate 8, a pair of relatively insulated power-supply conductor-connections 16 and 18 are provided; the connection 16 being intimately secured to the inner heating conductor 4 and the connection 18 being similarly secured to the outer heating conductor 6. The relatively insulated power supply connections 16 and 18 are supplied with high-frequency energy, generated in a high frequency generator 20 that feeds the generated current to them, either directly or through a suitable circuit 22 that may include a balancing network, or transformer, or other electrical circuit-improving element, as is known to the art.

It is necessary to provide a way of placing an object to be heat-treated into the work-receiving space 10 and then removing the object from the space after heating. To this end, the connection 16 to the inner heating conductor 4 can be made removable but other suitable expedients can be used.

For an understanding of the operation of the induction heater 2, it may be assumed that the high-frequency generator 20 is energized and is feeding high-frequency electrical power to the conductor-connections 16 and 18. It can be assumed that, at some instant, the current is flowing from the connection 16, downwardly along the outer surface of the inner conductor 4, radially outward on the inner surface of the connection-plate 8, and upwardly along the inner surface of the outer conductor 6, to the connection 18. Hence, each heating conductor has a pair of axially spaced points, one at each of its ends, to which circuit-connections (that is plate 8 and a connection 16 or 18) are secured. Such points on each heating conductor are axially spaced, one pair of spaced points (as 16 and 18) conductor lying on one axial side of the work-treating space 10 and the other pair of spaced points (as 4—8 and 6—8) lying on the opposite side.

The alternating current, flowing in the conductors 4 and 6, induces heating currents in the metal tubular object 12 which is carried on the piers 14, preferably concentric with the heating conductors. The induced currents will flow in each curved side of the tubular object, and in a direction opposite to the direction in which the current flows in the surfaces of the facing heating conductors. Accordingly, at the assumed instant, current will flow upwardly along the elements of the inner surface of the tubular object and downwardly along the outer surface of the tubular object. The current-path-circuit is com-

pleted in a radial direction at the ends of the tubular objects. The induced current heats the surfaces of the object in a manner understood in the art.

It is understood, of course, that the current flows in a thin surface-film having a thickness or depth which depends, among other things, upon the frequency of the power delivered by the high-frequency generator.

If it is found necessary to cool the heating nested conductors 4 and 6, an outer cooling-coil 24 may be helically wrapped around the outside surface of the outer conductor 6, in good thermal contact therewith, and an inner cooling-coil 26 may be disposed in contact with the inside surface of the inner conductor 4, which can be made hollow for this purpose, as shown in Figs. 1 and 2. The outer coil 24 has a water-inlet 28 and a water-outlet 30; and the inner coil 26 has a water-inlet 32 and a water-outlet 34, extending downwardly through the open bottom of the heating conductor 4.

Figures 3-6 show a more practicable structural form of my induction heater, indicated in its entirety by the reference numeral 40. The induction heater 40 comprises an inner copper heating conductor 42 and an outer copper heating conductor 44. In the preferred embodiment illustrated in Fig. 3, the outside diameter of the inner conductor 42 is one inch, and the inside diameter of the outer conductor 44 is three inches. The lower end of the inner conductor 42 has an integral outwardly extending flange or connection-plate 46, to which the lower end of the outer heating conductor 44 is firmly joined, for intimate electric contact. The conductors 42 and 44 are radially spaced to provide an annular work-receiving space 48 (Fig. 3) similar to the space 10 of Fig. 1.

The inner conductor 42 is hollow, having an open lower end and a closed upper end 50 that terminates in an upwardly extending threaded portion 52 which projects above the upper end of the outer heating conductor 44. The hollow part of the inner conductor 42 forms a channel-means 54, which is defined by the cylindrical wall 56 of the conductor 42, and which is perforated to provide outlet quench-openings for a quenching-liquid which is fed into the channel 54 in any suitable manner. Thus, said channel 54 may be supplied with a quenching-liquid through a pipe 58. The inner heating conductor 42 may be cooled, if necessary, by a helical cooling coil 60, which contacts the inside of the wall 56 and which is provided with water inlet and outlet-pipes 62 and 64, respectively, which extend downwardly through the lower end of the inner heating conductor 42.

The outer heating conductor 44 is also constructed so as to permit the outside of the work-piece to be quenched. To this end, the outer heating conductor 44 is hollow to provide an annular channel-means 68 therein. Specifically the outer conductor 44 comprises a solid or imperforate outer tubular wall 70, and a perforated inner tubular wall 72. Quenching liquid is supplied to the annular channel 68 of the outer heating conductor 44 by means of one or more liquid-supply pipes 76. For keeping the inner wall 72 of the outer heating conductor 44 cool, a cooling coil 74 is helically wound around it in intimate thermal contact therewith. This cooling coil is provided with water inlet and outlet pipes which liquid-tightly pass through the outer wall 70 of the outer heating conductor.

The work to be heat-treated is represented, in Figs. 3-5, as a ferrous bushing 78. It is carried on notched piers 80, which in turn are replaceably and snugly carried in grooves of a turntable 82 which is adapted to rotate around the lower end of the inner heating conductor 42. For rotating this turntable, a belt 84 is provided which passes through tubes 86 passing through the outer heating conductor 44.

The upper end of the outer heating conductor 44 has an integral flange or copper plate 90, that closes the upper end of the annular channel 68 in said conductor 44. This top-plate 90 has a central hole, corresponding in diameter to the inner diameter of the wall 72. Secured

to the underside of this top-plate 90 is a conductor-connection 92. Resting on the top-plate 90 is a layer of insulation 94 which separates said plate from a second conductor-connection 96. The connections 92 and 96 are equivalent to the connections 18 and 16 of Fig. 1. As shown in Fig. 4, the insulation 94, the lower connection-plate 92 and the upper connection-plate 96 have U-shaped cutout portions 98 that extend beyond a side of the outer heating conductor 44.

10 For electrically connecting the connection 96 to the inner heating conductor 42, a narrow copper securing-bar 100 is provided, having three spaced holes, the central one of which receives the extending threaded portion 52 of the inner conductor 42, and the end ones of which receive threaded bolts 102 and 104 that extend upwardly from the connection 96. Nuts 106 clamp the securing bar 100 in intimate contact with the connection 96 and with a flange 108 at the top of the inner heating conductor 42. Accordingly, whenever work is to be inserted into, or removed from, the work-receiving space 48, the securing bar 100 is first removed.

Assuming that work to be heated is in the space 48, the securing bar 100 is tightly bolted down, and the relatively insulated connections 92 and 96 are energized from 25 any suitable source of high-frequency energy. The turn-table 82 is rotated for rotating the work carried on the piers 80. After the desired heating interval, quenching-liquid is supplied to the channel-spaces 54 and 68 for 30 hardening the inner and outer surfaces of the bushing. Quenching liquid may flow out of the work-receiving space 48, through a plurality of spaced openings 109 in the bottom connection-plate 46. It is also to be observed 35 that the connection-bar 100 is of less width than the inner diameter of the outer heating conductor 44. Consequently, quenching-liquid can also flow upwardly through the resulting opening, including the cutout portions 98.

An induction heater in accordance with my invention may be used with practically any of the more common frequencies now used for induction heating. I have used 40 electric power derived from rotating alternators and from tube-oscillator generators. In a particular setup, such as shown in Fig. 3, I have successfully hardened both surfaces of a six-inch bushing by using current at a frequency of about ten thousand cycles per second and flowing 45 at eight thousand amperes. I have also used similar equipment for hardening with currents at considerably higher frequencies. The wave lengths are considerably longer than the work-piece 12 or 78, so that there are no significant standing-wave effects in the heating apparatus, 50 to produce non-uniform heating patterns in the work-piece.

In general, the object to be heated should have its axially extending curved surfaces radially spaced about equally from the heating conductors. Non-equal radial spacing 55 causes non-uniform current-distribution in Fig. 2. In Fig. 3, rotating the workpiece 78 produces even heating; even though the radial spacing may be non-equal. For this reason, it is desirable to rotate the piece.

While I have described my invention in connection 60 with an embodiment which is at present preferred, it is obvious that this embodiment is subject to considerable changes and modifications, and that the principles of my invention have considerably larger application, beyond that described in connection with the preferred embodiment.

65 I claim as my invention:

1. High-frequency inductive-heating apparatus, including a supporting-means for holding a hollow cylindrical conducting object having interior and exterior surfaces to be heated, and high-frequency inducing-current means 70 comprising an inner tubular inductor member and an outer tubular inductor member respectively positioned adjacent the interior and exterior surfaces of said object, for subjecting said surfaces to high-frequency current-inducing fields such as to induce high-frequency surface-skin cur-

rents which flow axially and in opposite directions along the respective interior and exterior surfaces of said object and radially at the ends of said object.

2. High-frequency inductive-heating apparatus, including a supporting-means for holding a hollow cylindrical conducting object to be heated, said object having substantially parallel interior and exterior surfaces, motor means for rotating said supporting-means about an axis which is approximately coincident with the axis of said object, and high-frequency inducing-current means comprising inner and outer tubular inductor members, said latter members being positioned adjacent respectively the interior and exterior surfaces of said object for subjecting said surfaces to high-frequency current inducing fields such as to induce high-frequency surface-skin currents which flow axially and in opposite directions along the interior and exterior surfaces of said object and radially at the ends of said object.

3. High-frequency heating apparatus of a type described, comprising, in combination, a plurality of nested heating conductors including an inner tubular induction heating conductor and an outer tubular induction heating conductor, said conductors extending in the same general lengthwise direction and being radially spaced to provide a work-treating space therebetween, work-supporting means for holding an axially extending workpiece in said space, said workpiece being positioned substantially parallel relative to said conductors, and circuit-means for supplying high-frequency current to said conductors, said circuit-means including circuit-connections between a pair of spaced connection-points on each of said conductors, said pairs of points being on opposite sides of the work-treating space, said circuit-connections including a direct cross-connection between a first of said points

5 10 15

on said inner conductor and a first of said points on said outer conductor, said first points lying at the same end of said work-treating space.

4. An induction heater of a type described, comprising, in combination, a pair of nested substantially parallel tubular induction heating conductors, said conductors being radially spaced to form a space for receiving work to be heated, conductor-means directly connecting an end-portion of the inner of said conductors to an end-portion of the outer of said conductors, said conductor-means being at an end of said space, means for supporting a metallic object in said space, with the inner conductor passing through said object, means for providing access to said space for loading and unloading said metallic object to and from said space, said means being at the other end of said space, and power-supply means associated with said conductors for causing high frequency currents to flow axially in said conductors.
